UNITED STATES PATENT OFFICE.

FRANCIS S. ADAMS, OF LEETONIA, OHIO.

APPARATUS FOR TREATING MOLTEN METALS.

940,774.

Specification of Letters Patent. Patented Nov. 23, 1909.

Application filed July 22, 1909. Serial No. 503,950.

To all whom it may concern:

Be it known that I, FRANCIS S. ADAMS, a citizen of the United States, residing at Leetonia, in the county of Columbiana and State of Ohio, have invented certain new and useful Improvements in Apparatus for Treating Molten Metals; and I do declare the following to be a full, clear, and exact description of the invention, such as will enable others skilled in the art to which it appertains to make and use the same.

This invention relates to an apparatus for treating molten metal for the purpose of reducing or eliminating the sulfur and the occluded gases.

The object of the invention is to provide a simple apparatus by means of which the above may be accomplished economically and within the minimum time, thus increasing the value of the apparatus commercially and for the useful arts.

With this and other objects in view, the invention consists of certain novel features of construction, combination and arrangement of parts, as will be more fully described and particularly pointed out in the appended claim.

In the accompanying drawings: The figure is a side elevation partly in vertical section of an apparatus embodying my improvements.

Referring to the drawings for a more particular description of the invention the apparatus comprises a substantially cylindrical vessel 1 provided with an inner lining 2 of fire brick or other equivalent material and with a removable cover 3. A pot 4 for the molten metal is provided with an inner lining 5 of fire brick and is mounted upon the bottom of the casing. Arranged in the casing with their lower ends immersed in the molten metal in the pot 4 is a pair of carbon electrodes 6 and 7 respectively, which are insulated from the metal in the pot by the fire brick cylinders 8 and are connected with the conducting wires 9 which may lead to a suitable source of current. These electrodes may be raised or lowered in the metal to provide greater or less heating surface by the following means:

Flexible elements 11 and 12 are suitably connected with the upper ends of the electrodes and pass over pulleys 13 and 14 mounted upon the horizontal arms 15. The upper ends of the elements 11 and 12 are connected with the upper ends of the cylind-

rical cores 16 which pass through solenoids 17 supported from the brackets 18. The solenoids are energized by the wires 19 which connect with batteries 20 while a rheostat 21 is arranged in the circuit to increase or decrease the current to energize the solenoids to a more or less extent, it being evident that by increasing the current through the solenoids that the core 16 will be drawn farther down and raise the electrodes a corresponding extent while by decreasing the current the electrodes will be permitted to lower into the metal.

A vacuum is created in the casing 1 by the vacuum pump 22 which is connected by means of a pipe 23 with the upper end of the barometric condenser 24. A second pipe 25 leads from the upper end of the casing 1 to the upper end of the condenser 24 while a third pipe 26 establishes communication between the pipe 25 and the pipe 23, valves 27, 28 and 29 being arranged in the pipes 26, 23, and 25 respectively.

In practice a vacuum may be created in the casing by means of the vacuum pump alone by closing the valves 28 and 29 and opening the valve 27 while a vacuum may be created in the casing by the barometric condenser which may be of the steam jet type by closing the valves 27 and 28 and opening valve 29 while the condenser and vacuum pump may operate together by closing valve 27, and opening valves 28 and 29 respectively.

In practice, the pot 4 containing the molten metal is placed in the casing 1. A vacuum is then-created in the casing as heretofore explained to reduce the pressure upon the metal to nearly zero in order to lower the boiling point and to increase the speed of vaporization of the sulfur contained in the metal. The occluded gases will also be freed more readily. The hottest metal in the pot rises to the surface and the vapors and gases given off will take heat from the surface, hence hotter metals will be constantly displacing the surface metal and this mechanical motion will bring every atom of metal to the surface at some time and its burden will be reduced. To keep the metal in a molten state hot enough to aid in the vaporization, an electric current is passed through the bottom of the metal as heretofore explained. By this method of eliminating the sulfur, ferro silicon, ferro-manganese and aluminum in iron and steel

the practice of poling copper in the refining of copper can be dispensed with. In eliminating the sulfur the oxids and sulfids are broken up and combine and pass off as sulfur dioxid. When it is found that there is not enough oxid present to cause all the sulfur to pass off, rollscale or oxid of iron may be constantly added until all of the sulfur has been eliminated in the molten iron.

10 From the foregoing description, taken in connection with the accompanying drawings, the construction and operation of the invention will be readily understood without requiring a more extended explanation.

15 I claim as my invention:

An apparatus for treating molten metal to eliminate the sulfur comprising a casing, a metal pot therein, means for creating a

vacuum in the casing, a pair of electrodes in the pot, means for passing a current 20 through the electrodes to heat the metal and electromagnetic means for raising or lowering the electrodes, said means comprising solenoids arranged in the casing, cores passing through the solenoids, flexible elements 25 between the upper ends of the cores and the electrodes, a source of current for the solenoids and means for varying the current through the solenoids.

In testimony whereof I have hereunto set 30 my hand in presence of two subscribing witnesses.

FRANCIS S. ADAMS.
